Application May 20, 1936, Serial No. 80,678

10 Claims.

(Cl. 229—21)

This invention relates to containers and more particularly to a paperboard container of generally rotund cross-section, in which the body and the bottom are integrally formed from a single blank of paperboard material.

In accordance with this invention a single blank of paperboard material of generally rectangular shape is divided into a body-forming portion and a bottom-forming portion by a score line extending transversely across the blank. The body portion of the blank is provided with a plurality of longitudinally extending score lines which are preferably comparatively closely spaced so as to divide the blank into a plurality of side 10 wall-forming segments so that when the body-forming blank is bent into tubular form, a body of generally rotund cross-section is provided. The bottom-forming portion of the blank is provided with two sets of score lines. One series of score 15 lines in the bottom-forming portion are substantially a continuation of the scores in the body-forming portion, while the other series of score lines are inclined to the first series of score lines so as to define a plurality of generally triangular shaped segments. When the bottom-forming portion has thus been scored the segments can be turned inwardly so as to lie substantially at right angles to the body-forming segment. When in 20 bottom-forming position the bottom-forming segments will lie in a "shingled" or generally overlapping relationship. The adjacent inner ends of the bottom-forming segments may be suitably connected together by a metallic clamp in the form of a button, clip, eyelet or gimlet, as circumstances require. The container is thus 25 completely assembled. A cover member for the container which telescopes into or over the open end of the container may be provided. The cover member may be formed similar to the container proper, comprising side wall segments forming 30 the flange of the cover and overlapping triangular-shaped end wall segments connected together by a suitable metallic clip to form the end portion of the cover.

My improved container can be economically assembled from a single blank of paperboard material with little or no waste cuttings resulting. The body and bottom-forming blank as well as the cover-forming blank may be cut to size and 35 scored on an automatic cutting and scoring machine. The side edges of the blank including the body-forming portion and the end-forming portion, may then be glued, stitched, or otherwise secured together to form a tubular sleeve. The 40 tubular sleeve is then placed in a suitable jig,

the bottom-forming segment turned inwardly and the center clip attached to the free ends of the end wall-forming segments to complete the bottom. The container as thus formed can be made at very low cost. To save shipping and storage 5 expense the tubular sleeve may be shipped and stored in a collapsed, flat form, the packer being provided with a container-forming jig which expands the sleeve in tubular form, turns the end wall-forming segments inwardly and applies the 10 center clip which connects the free ends of the end wall-forming segments. Considerable economy in shipping and storing the container is thus attained.

The container as thus made has a most attractive appearance. By providing a large number of vertical scores defining narrow side wall-forming segments, the container can be given a substantially circular, elliptical, or rotund cross-sectional contour, or, if desired, a polygonal 15 contour having five or more side wall panels. The end wall portion formed as above described presents a substantially flat surface on which the container may rest squarely, obviating the possibility of rocking movement. The end wall portion has a most pleasing rosette appearance 20 which can not only be economically formed but greatly enhances the beauty and attractiveness 25 of the package.

My novel container is adapted for the packaging of numerous products, such as confections, smoking material, baked goods, edible products, cosmetics, and numerous other articles of merchandise either in bulk or package form, which are normally packed in metal or paperboard 30 containers. The container may be given a smooth inside surface by inserting a bottom disk or plate within the container to rest on or adjacent to the end wall segments. A telescoping 35 cover may be provided for the open container, which is constructed similar to the container proper. If desired, a completely closed container may be formed by providing end wall-forming 40 segments at each end of the body-forming segments. In assembling such a container the end wall segments at one end of the body are sealed by a sealing clip, the contents are then inserted and finally the other end of the container is closed by sealing its end wall-forming segment. 45 To facilitate access to the contents the closure clip at one end of the container may be in the form of an open eyelet or gimlet, the opening therein being closed by a suitable stopper or cover. The granular or liquid contents can then 50

be poured out by simply removing the closure or stopper.

The container may be made liquid-tight and sift-proof by simply inserting some calking material around the edges of the sealing clip prior to the insertion thereof. The calking material should be in the form of a moldable mass, such as a bituminous, cellulosic, glutinous, resinous, or other plastic compound which is not affected by the liquid which is packed in the container. The calking material forms a complete seal between the connecting clip and the ends of the bottom-forming segments so as to completely seal the same. It will be noted that there are no cuts or other perforations in the bottom or body-forming blank, and by using waterproof, oilproof, or liquid-proof paperboard material, a substantial liquid-tight container is formed adapted for the packaging of such materials as ice cream and ices, liquid and semi-liquid food products, oils, and other liquid, semi-liquid or powdered products.

An object of this invention is to provide an attractive container which can be manufactured at low cost, which can be shipped in collapsed, knockdown condition to the user, which can easily and quickly be assembled by the user into container form, and which can be quickly packed and sealed to provide an attractive merchandising package.

Another object of this invention is to provide a container which may be made in substantially rotund form from a single blank of paperboard material, which is attractive in appearance, sturdy and strong in construction, and adapted for the packaging of numerous articles of merchandise.

Another object of this invention is to provide a paperboard container which is substantially liquid-tight and sift-proof.

Other objects of this invention will become apparent as the disclosure proceeds.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a perspective view of my improved container as it appears when fully assembled with a telescoping cover applied thereto;

Fig. 2 is a plan view of a blank which has been suitably cut and scored to form a cover member for the container body;

Fig. 3 is a plan view of a blank suitably cut and scored from which the body and bottom portions of the container may be formed;

Fig. 4 is an enlarged fragmentary plan view of the closed end of the container, which may be either the bottom or the cover end, certain parts being broken away to illustrate certain features of the construction;

Fig. 5 is an enlarged transverse cross-sectional view through the end portion of the container, this view being taken on line 5-5 of Fig. 4;

Fig. 6 is a vertical cross-sectional view through my container with the cover member applied thereto, this view illustrating the application of the connecting clip to the end wall segments for forming the container end wall;

Fig. 7 is a top plan view looking down on the end wall-forming segments as they appear at one

stage of the manufacturing operation prior to application of the end segment connecting clip;

Fig. 8 is an enlarged top plan view of one form of end wall segment connecting clip as it appears prior to the application thereof;

Fig. 9 is a vertical cross-sectional view through the end wall segment connecting clip shown in Fig. 8, this view being taken on line 9-9 of Fig. 8;

Fig. 13 is a plan view of a blank suitably cut and scored to form the container shown in Fig. 12;

Fig. 14 is an enlarged fragmentary cross-sectional view through the end wall structure of the container shown in Fig. 12, this view illustrating the manner in which the sealing clip may be applied to seal the container, and

Fig. 15 is an enlarged fragmentary top plan view of the container shown in Fig. 12, certain parts being broken away to illustrate certain features of the construction.

Similar reference characters refer to similar parts throughout the several views of the drawings and specification.

In accordance with this invention the body portion and an end wall or bottom portion forming the container proper may be assembled from a single blank of paperboard material A which has been suitably cut and scored, as illustrated in Fig. 3. A practical and commercially successful container having a generally rotund cross-section formed from a single blank of paperboard material has long been sought. The main difficulties encountered reside in the formation of a satisfactory end wall construction of the desired rotund form which would be attractive and neat in appearance, strong enough to support contents of considerable weight, and which would adequately retain and protect the contents. Where the term "rotund" is here used it is understood that a container substantially or entirely circular, round, oval elliptical, or partially or entirely curvilinear in cross-section, or having a polygonal cross-section with five or more side wall-forming faces, is indicated. It is acknowledged that containers having four side wall faces formed from a single blank of paperboard material are in common use. When a container of five or more side wall faces or containers of generally rotund form are to be made, however, difficulties are immediately encountered in the formation of a satisfactory end wall construction from the same blank from which the tubular body portion is formed.

This invention is addressed to the formation of containers from a single blank of paperboard material having a generally rotund cross-section as above defined. As shown more particularly in Fig. 3, the body and end wall or bottom-forming blank A is provided with a plurality of parallel extending score lines 2 defining side wall segments 1. The body portion of the blank may be divided into any number of side wall seg-

ments or panels 4 so as to obtain a container having a cross-section of any desired arcuate or polygonal contour. A transverse score line 6 defines the body-forming portion from the end wall-forming portion of the container. The end wall-forming portion comprises a plurality of substantially triangular-shaped end wall-forming segments 5 and 7 which are defined by the score lines 8 and 9. The score lines 9 are substantially a continuation of the score lines 2 in the body-forming portion of the blank, while the series of score lines 8 extend at an angle to and between each of the score lines 9. Preferably the inner ends of the score lines 8 meet the adjacent score lines 9 at or near the transverse score line 6, while the outer ends of the score lines 8 are positioned approximately midway between adjacent score lines 9. It is understood, however, that this invention is not limited to the particular arrangement of the score lines 8 as shown, but that they may be arranged at various angles to the score lines 9 to form containers of various forms, as will be evident to those skilled in the art.

In assembling the body and end wall-forming blank A the body tab portion 3 is glued, fixed or otherwise secured to the free vertical edge of the side wall-forming panel or segment 1 at the other end of the blank, so as to provide a generally tubular body. Similarly the end wall tab portion 10 is glued or otherwise secured to the free edge of the end wall-forming segment 5 at the other end of the blank, forming a tube which has the general appearance of the partially assembled container shown in Fig. 7. The cutting and scoring operation of the blank A can be performed on an automatic cutting and scoring machine and the gluing operation above described may be performed by an automatic gluer without hand operation. The glued blank as above described can be shipped and stored in flat, collapsed condition until ready for assembly in container form by the user.

The user is provided with a suitable jig, which need not be here specifically described, with which to assemble the container. The jig operates to push the end wall-forming segments 5 and 7 inwardly as shown in Fig. 7, so that the triangular segment 7 will fold under the adjacent segment 5 along the score lines 8 and 9, the segments 5 shingling or partially overlapping one another when the end wall is completely assembled. The end wall segments 5 and 7 can be turned with greater facility if a cut 11 is provided to separate the body-securing tab 3 from the end wall-securing tab 10. Preferably the cut 11 should extend short of the longitudinal score line 2, as shown in Fig. 3. The free ends of the end wall-forming segments 5 and 7 are firmly secured together by a suitable clip, clamp, seal, button, eyelet, gimlet, brace, or other securing means. The clip or clamping member is preferably formed of bendable metal but other material forming the clamping member may be used, as will be evident to those skilled in the art.

I have shown for purposes of illustration in Figs. 8 and 9 one form of sealing member which may be used. The sealing member here shown comprises generally two dish-shaped elements C and D having bottom wall portions 15 and 17 respectively. When an open container is to be formed, the bottom wall portions 15 and 17 of the sealing member may be spot-welded, as at 19 (Fig. 5) or otherwise firmly secured to-

gether. The side wall portions 16 and 18 of the respective dish-shaped elements C and D flare outwardly, as shown in Figs. 6 and 9, and the clamp can be easily inserted through the opening defined by the partially compressed end wall-forming segments 5 and 7. A suitable form block or anvil is inserted into the open container so that when the clamp member is compressed to the point where the end wall segments 5 and 7 extend substantially at right angles to the plane of the side wall-forming segments 1, the dish-shaped element D will rest on the form block or anvil. A compressive force such as pressure or blows is then delivered against the side walls 16 of the dish-shaped element C and preferably also against the side walls 18 of the dish-shaped element D so as to flatten the side wall portions 16 and 18 out so that they will assume the general form shown in Figs. 4 and 5 or 6. The dish-shaped elements C and D may be provided with tongue portions 20 which grip the adjacent paperboard material of the end wall segments 5 and 7 so as to securely lock the sealing member thereto and seal the end wall. A highly serviceable container is thus formed.

If a liquid-proof or sift-proof container is desired, a layer of calking material K may be applied to the adjacent outside areas of the side wall portions 16 and 18 of the clamping member, as shown in Figs. 6 and 9. When the side wall portions 16 and 18 have been clamped or stamped into position, the calking material K will spread out between the dish-shaped members C and D to seal the ends of the end wall-forming segments 5 and 7 so that liquid or powdered contents will not leak out through or around the edges of the clamping disks C and D. Any suitable form of calking material, preferably plasticisable in form, may be used. A calking material should be selected which will quickly harden and set, which is not affected by the contents, the atmosphere or by other outside influences, and which will not have any harmful effect on the contents. Plastic cellulose lacquer, where edible food products are to be packed in the container, may be used. Many other plasticisable calking materials may be used, for example, bitumens, resins, varnishes, latex, rubberous materials, animal or vegetable glues either in their natural form or mixed with powdered or granular base materials, packing materials, and cements. Many other plastics and calking materials in common use will occur to those skilled in the art as useful for the purpose, and it is understood that this invention is not limited to any particular form or type of calking material.

The open container formed from the body and bottom-forming blank A as above described, may be closed by a suitable telescoping cover, as shown in Figs. 1 and 6. The telescoping cover may be formed from a single blank of paperboard material B, as shown in Fig. 2, comprising a side wall of flange-forming portion defined from the end wall-forming portion by the transverse score line 6.

The cover-forming blank may be in all respects similar to the body-forming blank as shown in Fig. 3 and heretofore described. It is understood that if the cover member is to be telescoped over the open end of the body member, it should be slightly larger in size, and if the cover member is to telescope into the open body member it should be slightly smaller in size. The required measurements of the tubular container body and the cover member can be easily com-

puted by the boxmaker and need not here be described. The cover-forming blank comprises the flange-forming segments 1 defined by the score lines 2 and the end wall-forming segments 5 and 7 defined by the score lines 8 and 9. The cover-forming blank is secured together in tubular form by adhesively securing or otherwise attaching the securing tabs 3 of the flange portion and the securing tab 10 of the end wall-forming portion respectively to the free side edges of the flange-forming segments 1 and the free edge of the end wall-forming segments 5 at the other end of the blank. The construction of the cover member from the blank shown in Fig. 2 and the assembly thereof into a suitable cover is the same as that described in connection with the assembly and formation of an open container from the blank A shown in Fig. 3 and need not here be further described.

20 There is shown in Fig. 10 an enlarged vertical cross-sectional view through a container end wall of somewhat modified construction. The side wall-forming segments 1 and the end wall-forming segments 5 and 7 may be folded and arranged 25 in the manner hereinbefore described in connection with the construction shown in Figs. 2, 3, 4, 6 and 7. In this form of construction a somewhat modified form of sealing member E is provided. The sealing member here shown may be 30 in the form of a tubular member or eyelet having a tubular body portion 30 and spaced side wall portions 31 and 32. The eyelet E is applied to the end wall segments 5 and 7 in the same manner as the sealing member shown in Figs. 6, 35 8 and 9 and heretofore described. The flange portions 31 and 32 are pressed or clamped against the adjacent paperboard material of the end wall segments 5 and 7 by means of a suitable assembly jig. If desired, lips 33 may be provided on flange 40 portions 31 and 32 to maintain a firmer and more 45 secure grip on the end wall segments 5 and 7. The clamping member shown in Fig. 10 may also have calking material applied thereto so as to prevent leakage between the clamping member E and the adjacent end portions of the end wall-forming segments 5 and 7.

The clamping eyelet E may be closed by a suitable plug or stopper F. The end wall construction shown in Fig. 10 may be used at either the bottom 50 or top end or both ends of the container. The contents may be inserted into or removed from the container through the opening in the eyelet E, and it is thus seen that this form of construction is admirably adapted for certain uses where 55 it is preferable to completely assemble the container before the contents are inserted or where a container is desired having a convenient pouring opening through which the contents may be removed. When the contents have been inserted 60 the stopper F is applied, and when the contents are to be removed the stopper F can easily be withdrawn. Any form of stopper F, such as a cork, rubber or paperboard plug, or a metallic or paperboard disk stopper, or any well known 65 form of stopper may be used.

There is shown in Fig. 11 a further modified form of end wall sealing member which may be used. In the form here shown, a dish-shaped element C is positioned against the outside face 70 of the end wall segments 5 and 7. A false bottom or insert member 40 which may extend over the full area of the container is inserted into the tubular body. If desired, the insert 40 may be provided with supporting flanges 41 which closely 75 seat against the side wall segments 1. Filler

blocks 43 may be positioned between the dish-shaped element C and the insert 40 and these parts may be permanently secured together as by spot-welding or by the provision of a suitable rivet 45 having head portions 46 and 47 which seat against the dish-shaped element C and the insert 40 respectively. If desired, the insert 40 may be dispensed with and a second dish-shaped element C positioned against the inside face of the end wall-forming segments 5 and 7 may be 10 provided, both dish-shaped elements C being secured together as by spot-welding or by means of a suitable rivet 45 with or without filler blocks 43 positioned therebetween. The clamping element here shown may also be calked to provide 15 a substantially liquid-tight and sift-proof end wall construction.

There is shown in Fig. 12 a container having the tubular body portion and both end wall portions formed from a single blank of paperboard 20 material R cut and scored as shown in Fig. 13. In the construction here shown the side wall-forming segments 1 are defined by the longitudinally extending score lines 2 and the end wall-forming segments 5 and 7 are defined by 25 the score lines 8 and 9, as heretofore described. It has been found that a tighter connection between the ends of the end wall-forming segments 5 and 7 and the end wall clamping member may be had if the free ends of the segments 5 and 7 30 are given an arcuate cut 60, as shown in Figs. 13 and 15. When the end wall segments 5 and 7 as 35 here shown are pressed into end wall-forming position a substantially circular opening defined by straight cut edges is provided. Thus the opening 40 defined by the segments 5 and 7 pressed into end wall-forming position is defined by a smooth and regular edge which in some instances permits the end wall clamping member to retain a firmer and more positive grip on the free ends of 45 the end wall-forming segments 5 and 7. The exact shape of the arcuate cut-out 60 will depend upon the diameter of the container and the number of end wall-forming segments 5 and 7 with which it is provided, as is evident to those skilled 50 in the art.

One end of the container R may be closed by any suitable form of sealing clamp, as by the disk elements C and D, as shown in Fig. 12, which are applied to the end wall-forming segments by a 55 suitable jig. Where an anvil or assembly form cannot be inserted into the container to close the other end thereof, I preferably provide either an open eyelet element E, as shown in Fig. 10, or a button-shaped stud element G, as shown in Figs. 55 12 and 14. This button-shaped element comprises a head portion 50, a neck portion 52, and a shoulder portion 51 which rests against the inside face of the end wall-forming segments 5 and 7. A flange portion 53 flares outwardly as shown 60 in Fig. 14 when the button is inserted, after which the flanges 53 are clamped or bent down into firm clamping contact with the end wall segments 5 and 7. A rim portion 54 may be provided to retain a firmer grip on the surrounding end 65 wall segments.

The eyelets E shown in Fig. 10 or the buttons G shown in Fig. 14 may be applied by means of any suitable clamping tool or pincers. For purposes of illustration I have shown in Fig. 14 a 70 hand clamping tool which comprises the lever arms 100 and 101 having head portions 102 and 103 respectively, which are pivoted together by means of a suitable pivot pin 104. This hand tool has an anvil or face portion 107 provided on the 75

head portion 103 and a neck portion 108 having a suitably shaped nose 109 insertable through the neck-shaped opening of the button to seat within the button and behind the shoulder portion 51 thereof. When the handle portions 105 and 106 of the pivoted clamping members 100 and 101 are pressed together, the anvil portion 107 will bear down upon the flange portion 53 of the button and press the flange portion 53 and the shoulder portion 51 of the button into firm clamping engagement with the adjacent portions of the end wall-forming segments 5 and 7. The tool may be successively manipulated around the flange portion 53 of the button so as to clamp the entire button firmly in position.

It is understood that I also contemplate using automatic machinery for applying the eyelets E or buttons G to the end member. If a contents-inserting opening in the container is desired, one end wall of the container is preferably provided with an open eyelet E, such as shown in Fig. 10, which may be closed with a suitable stopper F. It will be evident that numerous forms of sealing members 25 may be provided within the purview of this invention and it will be understood that the end wall sealing clamps shown in the drawings are presented for purposes of illustration only and that other numerous forms of end wall closure 30 clamps may be provided within the purview of this invention.

Containers made as herein described may be given a perfectly round or curved contour by providing arcuate-shaped scores 61 in the body-forming blank, the arcuate scores 61 curving inwardly, as shown in Fig. 13, and joining the side wall segment-forming scores 2. The particular shape of the arcuate scores 61 will depend upon the diameter of the container to be formed. 40 When the blank is provided with suitable arcuate-shaped scores 61 adjoining the longitudinal scores 2 an accurately formed circular or arcuate-shaped container body will result.

The container as above described may be given a smooth interior end wall surface by the insertion of an end wall disk 49 into the body portion or the flange portion thereof as shown in Fig. 5. The insert disk 45 should be slightly oversize in dimensions so as to firmly press against the side wall-forming segments 1, thus stiffening the end wall and generally reinforcing the construction. The paperboard used in forming the container should possess a tough fibrous texture having a substantial degree of stiffness and rigidity. The 55 container herein described is highly serviceable for packaging loose products in bulk and may be made of any desired size.

While certain novel features of the invention have been disclosed and are pointed out in the 60 annexed claims, it will be understood that various omissions, substitutions and changes may be made by those skilled in the art without departing from the spirit of the invention.

What is claimed is:

65 1. A rigid contents-supporting container including, a tubular body portion and an end wall portion formed from a single blank of paperboard material, a series of longitudinally extending scores in said body portion defining side wall segments, a series of scores in said end wall portion formed substantially as a continuation of the longitudinal scores in the body portion, a second series of scores in said end wall portion extending at an angle to the first-mentioned scores therein, 70 said end wall scores defining end wall segments

adapted to lie in overlapping shingled relationship when arranged substantially at right angles to the side wall-forming segments, the inner ends of said end wall segments having a generally arcuate contour so as to define an end wall opening having generally smooth and even edges and gripping means connecting the free ends of said end wall segments to retain the same in end wall-forming position, said gripping means comprising a formable flange overlapping the inside face of 10 said end wall segments and a formable flange overlapping the outside of said end wall segments, means extending through the opening defined by the inner ends of said segments connecting said formable flanges, said flanges being pressed together by bending so as to firmly grip the ends of said segments extending therebetween.

2. A container end wall including, integrally connected overlapping segments formed from a single blank of paperboard material, the inner 20 ends of said segments having a generally arcuate contour so as to define an end wall opening having generally smooth and even edges, and means for connecting the inner ends of said segments.

3. A container including a tubular body portion 25 and an end wall portion formed from a single blank of paperboard material, a series of parallel extending scores in said end portion, a series of second parallel extending scores in said end portion arranged at an angle to said first mentioned scores, said scores defining connected end wall segments adapted to be arranged in overlapping shingled relationship, arcuate-shaped scores extending transversely to and connecting said first mentioned series of longitudinal scores, said arcuate scores defining the body portion from the end wall portion permitting said body portion to assume a true curvilinear form when said end wall segments are turned inwardly, the inner ends of said end wall segments having a generally 40 arcuate contour so as to define an end wall opening having generally smooth and even edges, and means for connecting said inturned end wall-forming segments in fixed end wall-forming relationship.

4. A container formed from a single blank of paperboard material including, a tubular body portion having a generally rotund cross section, an end wall portion comprising connected segments arranged in shingled relationship, and 50 means for connecting and sealing the adjacent inner ends of said end wall segments, said sealing means including a dish-shaped backing portion positioned within the container and overlapping said segments, and a dish-shaped outer portion 55 connected to said inner dish-shaped portion, said outer dish-shaped portion having a bendable flange extending over the outside surface of said end wall portion, said inner dish-shaped backing portion and said flange being pressed together 60 into sealing contact with the inner ends of said segments.

5. A container formed from a single blank of paperboard material including, a tubular body portion having a generally rotund cross-section, 65 an end wall portion connected to and extending inwardly from said tubular body portion, said end wall portion comprising connected segments arranged in shingled relationship, and means for connecting and sealing the adjacent inner ends of 70 said end wall segments, said sealing means including a pair of imperforate dish-shaped sealing elements having a portion extending through the opening defined by the inner ends of said segments connecting said sealing elements together, 75

said sealing elements having formable laterally extending flanges overlapping the inside and outside faces of said segments at the inner ends thereof, said flanges being pressed together into sealing gripping contact with the adjacent inner ends of said segments.

6. A paperboard container formed from a single blank of paperboard material including, a tubular body portion having a generally rotund cross-section, an end wall portion integrally formed therewith and extending inwardly substantially at right angles to said body portion, and means for sealing the opening defined by the inner end of said end wall portion, said means including imperforate disc-shaped closure elements closing said opening and overlapping the inner ends of said end wall portion with the end wall portion positioned between said disc elements, and a calking plastic positioned between said elements sealing the inner ends of said end wall portion with respect to said disc-shaped elements.

7. A container including, a tubular body portion and an end wall portion formed from a single blank of paperboard material, said end wall portion comprising integrally connected segments arranged in overlapping relationship, and means for sealing the inner adjacent ends of said segments, said means including a closure element having spaced formable flange portions overlapping of the opposed faces of the inner ends of said segments, said flange portions being pressed together into gripping engagement with the inner ends of said segments, and a calking plastic providing a tight seal between the inner ends of said segments and said flange portion.

8. A container including, a tubular body portion and an end wall portion formed from a single blank of paperboard material, said end wall portion comprising integrally connected segments arranged in shingled overlapping relationship, and means for sealing the inner ends of said segments, said means including a pair of spaced

closure elements each having a formable flange portion overlapping the respective inside face and outside face of said segments, means extending through the opening defined by the inner ends of said segments connecting said closure elements, said flange portions being pressed together to firmly grip the ends of said segments extending therebetween, and a calking plastic positioned between said flange portions sealing the inner ends of said segments in respect to said closure elements.

9. A container including, a tubular body portion and an end wall portion formed from a single blank of paperboard material, said end wall portion comprising segments arranged in overlapping relationship, means connecting the inner ends of said end wall segments and forming a contents-inserting and/or a contents-removing opening for said container, said means including a closure element having spaced formable flange portions overlapping the opposed faces of the inner ends of said segments, said flange portions being pressed together into gripping engagement with the inner ends of said segments, and a calking plastic providing a tight seal between the inner ends of said segments and said flange portions.

10. A container end wall including, integrally connected overlapping segments formed from paperboard material, means connecting the inner ends of said segments, said means including an open eyelet clamped to the inner end portions of said segments, said eyelet having spaced formable flange portions overlapping the opposed faces of the inner ends of said segments, the flange portions being pressed together into gripping engagement with the inner ends of said segments, a calking plastic providing a tight seal between the inner ends of the segments and said flange portions, and a closure for the opening in said eyelet.
